Whitaker & Prevost.

UNITED STATES PATENT OFFICE.

WASHINGTON FOGLESONG, OF DAYTON, OHIO.

HORSE-COLLAR HAMMER.

SPECIFICATION forming part of Letters Patent No. 391,133, dated October 16, 1888.

Application filed February 28, 1888. Serial No. 265,544. (No model.)

To all whom it may concern:

Be it known that I, WASHINGTON FOGLESONG, a citizen of the United States, residing at Dayton, in the county of Montgomery and State of Ohio, have invented certain new and useful Improvements in Horse-Collar Hammers; and I do hereby declare the following to be a full, clear, and exact description of the invention, such as will enable others skilled in the art to which it appertains to make and use the same.

My invention relates to horse-collar hammers, and has for its object to provide a construction which will give sharp elastic blows in rapid succession.

I have illustrated my invention in the accompanying drawings, and said invention is fully disclosed in the following specification and claims.

In the drawings, Figure 1 is a side view of my improved collar-hammer. Fig. 2 is a section on line x x , Fig. 1. Figs. 3, 4, 5, and 6 are detail views showing modified forms of my invention. Fig. 7 is a view showing the means by which the anvil is made adjustable.

In the drawings, Δ is the main frame of the machine, mounted on a suitable base, B . The main frame may be hollow or solid, as preferred; but in either case it is provided with the recess a in the rear part of the same. Upon some portion of the frame, preferably at a point adjacent to the recess a , are mounted, in any preferred manner, two standards, C C , the upper ends of which approach each other and are connected by a bolt, c . Upon the bolt c , as a journal, is mounted the lever D , which is provided with two perforated ears, d d , near its center, to engage the journal, and upon the bolt c , between the two ears d d , is mounted the hammer-arm E . The hammer-arm may consist of one bar, as shown in Figs. 1, 3, 4, and 5; or it may consist of two connected parallel bars or of one bar provided with two parallel arms, as shown in Fig. 6.

The lever D is provided at its rear end with a smooth cylindrical portion, d' , which terminates in a cap or shoulder, d'' , and the opposite end is preferably provided with the two perforated circular projections d'' .

In my preferred construction illustrated in Figs. 1 and 2 the hammer-arm E has a

widened portion, e , directly under the ears d'' , which is provided with two slots or apertures. Through the ears d'' and the apertures in the part e of the hammer-arm pass the bolts F F , 55 provided on their outer ends with nuts, and also provided at their lower ends with the washer H . Around the bolts are placed the spiral springs G G , one above and one below the hammer-arm, the slots in the part e of the hammer-arm being large enough to permit of vertical movement upon the bolts F . I may, however, use but one bolt F , if preferred, and I may also use but one spring G , and provide the portion e of the hammer-arm with lugs to 65 engage the coils of the spring in the center of the same.

In Figs. 3, 4, 5, and 6 I have illustrated modifications of my construction, in which I employ a flat steel spring instead of a spiral 70 spring, as in my preferred form.

In the form shown in Fig. 5 I employ one or two flat springs G , which are attached to the hammer-arm at or near the head of the hammer. The springs are secured at another 75 point on the hammer-arm by passing through a staple, g , or two lugs provided on the arm, or in any other preferred manner. The other end of the spring G is then attached to the end of the lever D by means of a link or other connection. By this means the same elasticity 80 may be secured and very good results produced thereby.

In Fig. 4 I have shown a spring attached in this manner on both sides of the hammer-arm, 85 and in Fig. 6 I have shown the hammer-arm, consisting for a portion of its length of two parallel bars and a single spring, attached to the hammer-arm, between the bars, in a similar manner.

Fig. 3 represents a slightly different form of hammer, in which I mount the hammer-arm on standards C' separate from the standards C . To the rear end of the hammer-arm is rigidly attached a flat steel spring, which is connected 95 at its other end to the lever D by a suitable link. This construction also provides the elastic connection which is necessary to give the hammer an elastic blow.

Upon the side walls of the recess a of the 100 main frame is journaled the shaft K , which is provided with a crank or eccentric, k , between

the bearings. This crank is connected, by means of a rod or pitman, L, with the sleeve M, which is mounted upon the cylindrical part d' of the lever D. This sleeve is provided 5 with ears m, which engage the end of the connecting-rod or pitman, and also with a binding-screw, m', which clamps the sleeve at any point upon the arm of the lever D.

Upon one end of the shaft K, outside of 10 the main frame, is loosely mounted the band-pulley N, provided with a suitable clutch mounted rigidly upon the shaft, which is thrown into and out of engagement with the band-pulley by means of a yoke, O, on the end 15 of the lever P, which is mounted in brackets p, cast or otherwise secured to the main frame A, and this lever passes through slots in the sides of the main frame to the opposite side of the machine.

20 The end of the lever P is connected, by means of a rod, p', to a foot lever or treadle, Q. This lever is preferably U-shaped, and embraces the base of the machine, extending around the front side of the same, and its free ends are 25 pivoted on both sides of the rear end of the frame.

The rod p' is attached to the lever Q at a point a little distant from the pivot upon that side of the frame, and the curved portion of 30 the lever Q is held in a raised position above the floor by a spring or other yielding device, and by this construction the lever may be operated from any part of the machine. When the lever is depressed, it will draw down the 35 rod p', connected to one end of the lever P, which will also be depressed, thereby throwing the clutch into engagement with the band-wheel N, which is rotated constantly by means of a driving-belt. The clutch will then cause 40 the shaft to revolve with the band-wheel, and the crank or eccentric of the shaft will produce an oscillating movement of the lever D, which, by acting through the intervention of the springs G, will cause the hammer to strike 45 the elastic blows upon material placed upon the anvil R, which is mounted upon the main frame under the head of the hammer.

The movement of the lever D is not sufficient of itself to force the hammer down to the 50 point at which the blow is to be delivered. Upon the first downward movement of the lever D the spring G above the hammer arm will be slightly compressed, and as the lever and hammer-arm are carried downward the 55 inertia of the hammer and the force of the slight compression of the spring will carry the hammer down with a sharp elastic blow upon the material, which will effect a very slight compression of the spring G below the hammer-arm. The recoil of this lower spring will 60 tend to throw the hammer-arm up immediately, even before the return movement of the crank-arm tends to raise it. It is a well-known fact that for certain purposes a light 65 sharp elastic blow from a hammer is preferable to a hard solid blow, and is in reality more

effective, and it is this sharp elastic tap or blow which I effect by my construction.

While I have shown my operating mechanism as applied to my preferred construction 70 of hammer-arm, it is obvious that it may be applied to the modified forms shown and described in the same manner.

The position of the sleeve M may be regulated upon the lever D to produce harder or 75 lighter blows, as may be desired.

The anvil is preferably made adjustable by means of a screw construction, as shown in Fig. 7, or otherwise, so that it may be raised or lowered to accommodate material of different thickness or to regulate the force of the blow of the hammer, as may be desired. 80

While I have described my invention to be used for hammering collars, it may be used to hammer seams, nail boxes, and for any other 85 purposes for which it may be found desirable.

In Fig. 5 I have shown the spring attached rigidly to the hammer-arm and connected to the vibrating arm D by a link. I may, however, prefer to attach the spring rigidly to the 90 vibrating arm and extend it to a point nearly over the head of the hammer and connect it thereto by a link, as shown in dotted lines.

What I claim, and desire to secure by Letters Patent, is—

1. In a leather-hammer, the combination, with a vertically-adjustable anvil, of a vibrating arm and a hammer-arm, the two being connected by an elastic connection permitting the elastic movement of the hammer-arm toward and from the vibrating arm of a crank-shaft, and a pitman connecting the crank-shaft and vibrating arm, substantially as described. 100

2. In a leather-hammer, the combination, with a vertically-adjustable anvil, of a vibrating arm and a hammer-arm, the two being connected by an elastic connection permitting the elastic movement of the hammer-arm toward and from the vibrating arm of a crank-shaft, and a pitman connecting the crank-shaft and vibrating arm, the connection between the pitman and vibrating arm being adjustable 110 toward and from the pivot of the vibrating arm, substantially as described.

3. In a leather-hammer, the combination, 115 with a pivoted hammer-arm, of a vibrating arm extending above said hammer-arm, two coiled springs interposed between the hammer-arm and the end of said vibrating arm, two rods, each passing through one of said 120 springs and through said hammer-arm, two coiled springs each encircling one of said rods between the hammer-arm and the end of the same, a washer on said rods and securing means, and a pitman and crank for operating 125 said vibrating arm, substantially as described.

In testimony whereof I affix my signature in presence of two witnesses.

WASHINGTON FOGLESONG.
